Inventor:

Gaines M. Walker,

By Higdon & Longworth Attn'ts.

UNITED STATES PATENT OFFICE.

GAINES M. WALKER, OF ST. LOUIS, MISSOURI.

BASKET.

1,261,982.

Specification of Letters Patent. Patented Apr. 9, 1918.

Application filed June 1, 1914. Serial No. 842,272.

To all whom it may concern:

Be it known that I, GAINES M. WALKER, a citizen of the United States, and resident of St. Louis, Missouri, have invented certain new and useful Improvements in Baskets, of which the following is a specification containing a full, clear, and exact description, reference being had to the accompanying drawings, forming a part hereof.

10 My invention relates to improvements in baskets, in which the body of the basket is made of a single piece of material, and it is the object of my improvements to construct the body of the basket from a single 15 piece or blank of material having at opposite margins pairs of spaced apart kerfs and otherwise free from cuts or scores, so that all folding lines of the basket have the full strength of the material and so that the 20 perforate blank may be formed into a basket which will not leak.

With the above and other objects in view, which will be made clear, my invention consists in the construction of basket fully set 25 forth in the following specification, pointed out in my claims and illustrated by the accompanying drawings, in which—

Figure 1 shows in plan a blank out of which the body of my improved basket may 30 be made;

Fig. 2 shows in perspective a basket embodying my improvements;

Fig. 3 is an enlarged detail plan showing a diagonal cut at the inner end of a kerf to 35 prevent splitting of the material;

Fig. 4 is an enlarged detail perspective showing the non-leaking joint at a corner of the basket;

Fig. 5 is a plan of the complete basket;

Fig. 6 is an end elevation of the basket;

Fig. 7 is a longitudinal sectional elevation;

Fig. 8 is a transverse sectional elevation;

Fig. 9 is an inverted plan of the basket;

Fig. 10 is an end elevation showing a plurality of nested basket bodies; and

Fig. 11 is an enlarged sectional elevation of the material from which the baskets are formed.

50 Referring to the drawings:

Fig. 1 illustrates the blank, constructed of a single piece of material, and which comprises the central body portion designated by the numeral 12, which portion is defined

by the broken lines 13—14—15—16, and 55 which portion constitutes the bottom of the basket.

At the ends of the portion 12 (bottom) there are the portions 17 and 18, whose widths are substantially the same as the 60 width of the portion 12 (bottom) and whose lengths are governed by the height of basket desired. These portions 17 and 18 constitute the ends of the basket.

At the sides of the portion 12 (bottom) 65 and above and below, respectively, the lines 14 and 16, are the portions 19 and 20, whose lengths are the same as the portion 12 (bottom) and whose widths are the same as the 70 lengths of the portions 17 and 18 (ends) and which portions 19 and 20 constitute the sides of the basket.

The portion 19 (side) carries at its ends 75 the wings (auxiliary ends) 21 and 22, and the portion 20 (side) is likewise provided with wings 23 and 24 (auxiliary ends).

As shown, all of the wings (auxiliary ends) are separated from the portions 17 and 18 (ends) by kerfs 25, so that the auxiliary ends may overlap the ends. 80

Each of the wings 21—22—23 and 24 (auxiliary ends) have their outer side margins 26 disposed at oblique angles relative to the side margins of the portions 19 and 20 (sides). 85

The degree of the angle of these margins just referred to depends solely on the desired angularity of the sides of the basket. If the sides of the basket are vertical, then these margins of the auxiliary ends should 90 be parallel with the side margins of the sides, and if the sides of the basket flare outwardly and upwardly, then these margins 26 should be formed at an angle complementary to the angle of the sides of the basket. In this manner the upper margin of the basket needs no shaping or trimming after the basket is formed.

The inside margin of each wing (auxiliary end) formed by the kerf 25 is preferably disposed at an oblique angle relative to the adjacent margin of the basket end (17 or 18) in order to shorten the end margins of the wings, hence lessen the number of staples or other securing devices, such as 27, for securing the auxiliary ends to the ends proper. 100

At each outer, free margin of the sides 19 and 20, and extending the length thereof, is 105

a reinforcing strip 28, and at the outer free margin of the ends 17 and 18 are the reinforcing strips 29, these strips when the basket is formed constituting an inner rim for the basket.

The material entering into this blank is by preference thin wood veneer, reinforced by paper glued to the entire surface of the veneer, as shown in detail in Fig. 11, where-
10 in A designates the veneer and B the paper and C the glue.

The dotted lines in Fig. 1 simply define the different portions of the blank and are not to be understood as indicating scores, 15 but do however approximate the folding lines between the different parts.

In this connection I want it distinctly understood that all folding lines in my complete basket are curved in order to prevent 20 breakage of material, so that there obtains a maximum strength of material along these folding lines.

In forming a basket body from a blank such as shown, I first bend the basket ends 25 17 and 18 at or near right angles relative to the bottom, then bend the sides 19 and 20 at or near right angles to the bottom, then bend the auxiliary ends 21—22—23—24 to overlie the ends 17 and 18 and overlap 30 each other at their inner ends.

After thus shaping the basket body, I secure the ends and auxiliary ends by staples 27, which extend through the overlapped ends of the auxiliary ends 21—22—23 and 35 24 and through the ends 17 and 18.

If the wood veneer is straight grained, I exercise care in the making of the material to have the grain extend lengthwise of the blank, for by this arrangement the corners 40 of the basket are folded on lines crosswise of the grain and hence the veneer has maximum strength at the corners.

In order to prevent splitting of the veneer between the kerfs 25, I resort to the expedient of the diagonal cuts at the inner ends of the kerfs and which extend at an angle relative to the grain of the veneer.

An additional advantage incident to the cuts 31 is that when the ends 17 and 18 are 50 folded as on the lines 13 and 15, and when the auxiliary ends are folded to overlap the ends, there are formed gores, such as 32, which completely close the joints and prevent leakage.

55 These basket bodies due to the absence of outside rims may be almost completely telescoped, and hence will nest advantageously for shipping.

33 designates the basket handle, which is 60 applied by slipping its ends between the basket body and the rims 28, and secured in place by the staples 34 which secure it to

the basket body and by the staples 35 which secure it to the basket rims.

Having thus described my invention, what 65 I claim as new therein and desire to secure by Letters Patent, is:

1. A basket constructed of a blank made from a single piece of material and comprising a substantial rectangular bottom, substantially rectangular sides forming unbroken continuations of the bottom and disposed parallel along opposite margins of the bottom, substantially rectangular ends proper forming unbroken continuations of the bottom 75 along margins opposite said sides, the length of said ends being substantially equal to the width of the sides, strips forming inner basket rims secured to the inside faces of said sides and to the ends, the side strips 80 being unattached intermediate their lengths to afford a passage way for a handle, and auxiliary folding ends forming unbroken continuations of the sides, the said ends being cut away or unattached to the ends 85 proper of the box so that the same may be folded independently of the ends proper and a handle located between the side basket rims and the sides of the basket.

2. A basket constructed of a blank made 90 from a single piece of wood veneer covered with paper so that the same may be bent into box form without disturbing the wood fiber and forming cracks, and comprising a substantially rectangular bottom, substantially rectangular sides forming unbroken continuations of the bottom and disposed parallel along opposite margins of the bottom, substantially rectangular ends proper, the lengths of which being equal to the 95 width of the sides and forming unbroken continuations of the bottom along margins opposite said sides, inner basket rims secured to the inside faces of said sides and ends, the ends of the side strips and end 100 strips being spaced apart so that the corners of the box are free from rims, the said side strips being free to be removed from the sides to afford a passage for a basket handle, and auxiliary end flaps having inner 105 margins cut away and inclined and capable of being folded upon each other to cover the entire side margins of the ends proper so as to completely close the ends of the basket and to hold the basket when the same are 110 secured together in the desired shape.

In testimony whereof I have signed my name to this specification in presence of two subscribing witnesses.

GAINES M. WALKER.
